US00D805998S

(12) **United States Design Patent** (10) Patent No.: **US D805,998 S**
De Carvalho et al. (45) Date of Patent: **** Dec. 26, 2017**

(54) **AIRCRAFT FUSELAGE**

(71) Applicant: **EMBRAER S.A.**, São José dos Campos/SP (BR)

(72) Inventors: **Carlos Eduardo De Carvalho**, São José dos Campos (BR); **Alessandro Vassallo**, São José dos Campos (BR); **Amanda Oliveira Do Carmo**, São José dos Campos (BR); **André Gasparotti**, São José dos Campos (BR); **Bruno Kimura Castanha**, São José dos Campos (BR); **Carlos Augusto Fernandes Filho**, São José dos Campos (BR); **Carlos Marcelo Campos Teixeira**, São José dos Campos (BR); **Carlos Rosley Bernardes**, São José dos Campos (BR); **Demetrio Andrade De Campos**, São José dos Campos (BR); **Douglas De Albuquerque**, São José dos Campos (BR); **Emmanuel Basile Garakis**, São José dos Campos (BR); **Fernanda Loth Pugliesi**, São José dos Campos (BR); **Luz Maria Romero Tarazona**, São José dos Campos (BR); **Mateus Rodrigues Miranda**, São José dos Campos (BR); **Mauri Mendes De Oliveira**, São José dos Campos (BR); **Ricardo Athayde Abelheira**, São José dos Campos (BR); **Silvio Hideo Lemos Mochiduky**, São José dos Campos (BR); **Sergio Raphael Fonseca Affonso**, São José dos Campos (BR); **Walter Affonso Junior**, São José dos Campos (BR)

(73) Assignee: **EMBRAER S.A.**, São José Dos Campos, SP (BR)

(**) Term: **15 Years**

(21) Appl. No.: **29/536,662**

(22) Filed: **Aug. 18, 2015**

(57) **CLAIM**

The ornamental design for an “aircraft fuselage,” as shown and described.

DESCRIPTION

FIG. 1 is a left-front perspective view of an embodiment of an aircraft fuselage showing our new design thereof;

FIG. 2 is a right-front perspective view thereof;

FIG. 3 is a top plan view thereof;

FIG. 4 is a left side elevational view thereof; and,

FIG. 5 is a right side elevational view thereof.

The broken lines in FIGS. 1-5 represent structures in the environment of the claimed design which do not form any part of the claimed design.

The dot-dash-dot lines in FIGS. 1-5 represent boundaries of the claimed design which do not form a part of the claimed design.

1 Claim, 4 Drawing Sheets
